US0D1031174S

(12) United States Design Patent (10) Patent No.: US D1,031,174 S
(45) Date of Patent:  *Jun. 11, 2024

(54) MASK

(71) Applicant: Jae Won Shin, Seoul (KR)

(72) Inventor: Jae Won Shin, Seoul (KR)

(*) Notice: This patent is subject to a terminal disclaimer.

() Term: 15 Years

(21) Appl. No.: 29/847,384

(22) Filed: Jul. 25, 2022

(30) Foreign Application Priority Data

Jun. 20, 2022 (KR) 30-2022-0024461

(51) LOC (14) Cl. 29-02

(52) U.S. Cl.

USPC D29/108

(58) Field of Classification Search
